UNITED STATES PATENT OFFICE.

E. L. GAYLORD, OF TERRYSVILLE, CONNECTICUT.

IMPROVEMENT IN HASP-LOCKS.

Specification forming part of Letters Patent No. 93,078, dated July 27, 1869.

To all whom it may concern:

Be it known that I, E. L. GAYLORD, of Terryville, in the county of Litchfield and State of Connecticut, have invented a new and useful Combination of a Hasp-Lock and Thumb-Bolt; and I do hereby declare that the following is a full, clear, and exact description of the same, reference being had to the accompanying drawings and the letters of reference marked thereon, making a part of this specification.

This invention relates to a new and useful combination of a hasp-lock and thumb-bolt, which is applicable to trunks, boxes, and all articles which are provided with a hinged lid. The invention, however, is more especially designed for fruit-crates, such as are used for conveying berries and other small fruit to market. At present a lock of usual construction—in most cases a padlock—is applied to the crates, and the time and trouble in locking and unlocking the same preclude such, or any other lock, being used when the fruit is on sale at the "distributing center." The crates consequently are kept in an exposed and unlocked state and liable to be injured and stolen.

My invention admits of the lids of the crates being temporarily fastened by the thumb-bolt so that they can be opened and closed rapidly while showing the fruit to customers at the distributing center, the thumb-bolt being used for this purpose, while all the advantage and security of a lock is obtained when the latter is required, as in shipping the fruit from the distributing center to the localities of the retail or small dealers.

In the accompanying sheet of drawings, Figure 1 is front view of my invention; Fig. 2, a detached inner side view of the lock, showing its interior construction.

Similar letters of reference indicate corresponding parts in the two figures.

To enable those skilled in the art to fully understand and construct my invention, I will proceed to describe it.

A represents a hasp, and a the joint thereof, which connects the two parts b c of the hasp, the part b being attached to the lid of the crate or other article, and the part c allowed to swing or hang freely from the lower end of b, as will be fully understood by referring to Fig. 1.

B is a socket which projects from a plate, C, the latter being attached to the front of the body of the crate, and in such a position rela-

tively with the lower part, c, of the hasp as to admit of the socket B, when the hasp is in contact with the front of the crate, passing through an opening in C to allow said socket to receive the bolt of the lock when the bolt is thrown down under the action of the lock-key, and the lid of the crate thereby locked.

D is a lock, which is permanently attached to the hasp A. This lock is composed of a bolt, d, which is actuated by a key, said bolt being a sliding one, and having a spring, e, bearing against it to prevent any casual movement. (See Fig. 2.) Besides this bolt d there is within the same case another one, f, which is a thumb-bolt, and is by the side of the lock or key-bolt d, the same spring, e, serving for both bolts. The thumb-bolt f extends through the top of the lock-case, and is formed with a lateral projection, g, at its upper end, to admit of the bolt being raised by the thumb and drawn out from the socket B. It will be seen, of course, that either bolt may be operated independently of the other. In cases where the lids of the crates require only a temporary fastening—as, for instance, when in the distributing center—the thumb-bolt f is only used, the lock or key-bolt being raised out of the socket. The thumb-bolt may be actuated with the greatest facility, and, although only a temporary fastening, answers every purpose for preventing the handling of the fruit and the pilfering thereof, when on sale at the locality above mentioned.

This device may be constructed at a very moderate cost, equally so as any of the hasp-locks hitherto made, and cheaper than an ordinary hasp-lock, and a separate or independent slide-bolt or catch.

I do not claim, broadly, applying and affixing a lock to a hasp, as I am aware that such is not new; but,

Having thus described my invention, what I claim as new, and desire to secure by Letters Patent, is—

The lock-bolt d and thumb-bolt f g, constructed substantially as described, when so arranged that the spring e presses directly against the former, and through it exerts pressure on the latter, substantially as and for the purpose set forth.

E. L. GAYLORD.
